UNITED STATES PATENT OFFICE.

DANIEL NEWTON ALLARD, OF POMEROY, OHIO.

PLUMB-LEVEL.

SPECIFICATION forming part of Letters Patent No. 729,521, dated June 2, 1903.

Application filed July 16, 1902. Serial No. 115,865. (No model.)

To all whom it may concern:

Be it known that I, DANIEL NEWTON ALLARD, a citizen of the United States, residing at Pomeroy, in the county of Meigs and State of Ohio, have invented certain new and useful Improvements in Plumb-Levels, of which the following is a specification.

This invention relates to leveling instruments, and has special reference to an improvement in that type of devices employed by mechanics for leveling purposes.

To this end the invention contemplates a simple and practical construction of plumb-level comprising means for securing a perfect leveling of any piece of work and possessing special utility as a level for the use of bricklayers and carpenters. Of course the invention contemplates a plumb-level capable of general application to any use to which such a device may be placed.

In carrying out the invention the same has in view a novel construction of level which shall be much more accurate and more easily handled than the common plumb-bob, while at the same time accomplishing all of the advantages and functions of that type of levels known as "spirit-levels."

A further object of the invention is to so construct the level as to provide for proper indications being given irrespective of the position in which the leveling-bar may be placed, thus enabling the mechanic at times to secure from his level an indication.

The invention also has in view a construction wherein the indicating part of the level is visible from both sides or faces of the leveling-bar, as well as from the top thereof, and also one in which the various parts are readily removable and replaceable and are also protected from breakage.

With these and many other objects in view, which will more readily appear as the nature of the invention is better understood, the same consists in the novel construction, combination, and arrangement of parts, as will be hereinafter more fully described, illustrated, and claimed.

The essential features of the invention involved in the instrumentalities for carrying out the above objects are necessarily susceptible to modification without departing from the spirit of the invention; but a pre-

ferred embodiment of the latter is shown in the accompanying drawings, in which—

Figure 1 is a perspective view of a plumb-level constructed in accordance with the present invention; Fig. 2 is an enlarged vertical sectional view thereof. Fig. 3 is a vertical longitudinal sectional view on the line 3 of Fig. 2. Fig. 4 is a detail perspective of the preferred type of self-adjusting indicator employed.

Like reference-numerals designate corresponding parts throughout the several figures of the drawings.

In the carrying out of the invention any suitable type of level-body may be employed; but this preferably consists of an oblong or rectangular straight bar designed to be placed upon or against the work to be leveled, said bar constituting a leveling-bar and being designated in the drawings by the numeral 1.

The present invention contemplates a separable assembling of the working parts of the indicating device and the removable housing thereof within the body of the leveling-bar 1, besides so constructing the latter that indications may be observed from either side or the top of the same. To secure this desirable result, the body of the leveling-bar 1 is provided therein with a holding-mortise 2, preferably of rectangular formation. This holding-mortise 2 is sunk into the body of the bar from what may be properly termed the "top" or upper side 3 thereof, thereby forming in the top of the leveling-bar a rectangular top observation-opening 4, through which observations may be made when the lower side or bottom thereof is placed upon a wall or other piece of work.

In addition to the top observation-opening 4, the side faces of the leveling-bar 1 are pierced by the arched or crescent-shaped side observation-openings 5, which subserve the useful function of exposing indications in any and all angles of the leveling-bar, while at the same time leaving a solid portion within the circle of the said crescent-shaped or segmental openings, which acts as a guard or protection to the glass face-plates of the indicating device which is housed within the holding-mortise 2.

The indicating device, which is housed within the mortise 2, essentially consists of a cas-

ing 6, comprising a rectangular body loosely, though snugly, registering within the mortise 2. The body of the casing 6 includes end walls or strips 7, the top and bottom strips 8 and 9, secured, respectively, to the upper and lower edges of the end strips 7 and of a greater width than the latter to project beyond the side edges of the end walls or strips, and thus provide at opposite sides of the casing-body 10 seats within which are removably received the glass face-plates 9, constituting the sides of the casing and held in their assembled relation within the seat by reason of the registering fit of the indicating device as an entirety within the holding-mortise 2.

The side face-plates 9 of the casing 6 are preferably provided with suitable indications or graduations 10 thereon, which are exposed through the windows provided by the side 20 observation-openings 5, and at this point it is to be observed that the top strip 8 of the indicator-casing is likewise of glass and is provided with an indicating-point or graduations 11, exposed through the top observation-opening 25 4.

The casing described is removably held within its holding-mortise through the medium of a cover-plate 12, seated flush within the top side of the leveling-bar and having 30 an opening 13, exposing the glass-covered observation-opening 4 at the top of the leveling-bar.

Coöoperating with the indications or graduations of the side face-plates 9 and the top 35 glass strip 8 is a self-adjusting oscillating indicator 14. The said self-adjusting oscillating indicator 14 is of the weighted type and is mounted upon a pivot 15, journaled in the face-plates of the casing, whereby the indicator is thus held suspended, so as to be exposed through either of side face-plates or the top glass strip 8.

Preferably in the carrying out of the invention the indicator 14 essentially consists of the body having the weighted section 16 below the pivotal point thereof and provided with a plurality of radially-disposed pointers 17 and 18, the pointer 17 being the main or central pointer and lying between the oppositely-extending side pointers 18. All of the 45 said pointers are provided at their outer ends with indicating-heads 19, having guide marks or notches 20 therein. With the leveling-bar in a horizontal perfectly-level position the 50 side pointers 18 lie at the extremities of the

crescent-shaped or segmental observation-openings 5, while the central pointer 17 has its indicating-head directly opposite the central mark or graduation on the top strip 8.

From the foregoing it is thought that the 60 construction, operation, and many advantages of the herein-described plumb-level will be readily apparent without further description, and it will also be understood that various changes in the form, proportion, and 65 minor details may be resorted to without departing from the spirit or sacrificing any of the advantages of the invention.

Having thus described the invention, what is claimed, and desired to be secured by Letters Patent, is—

1. In a plumb-level, a bar having a holding-mortise and provided with top and side openings in communication therewith, an indicator-casing seated within the mortise and 75 having transparent top and side walls, the top being provided with an indicator or gage mark and the side walls with degree-indicating marks, a plural-armed gravity-indicator pivotally mounted within the casing and provided with designating marks or notches, those of the central arm coöperating with the indicating-marks on the top and both side walls of the casing.

2. In a plumb-level, a bar having a holding-mortise cut into the upper portion of the bar, arcuate side openings communicating with the mortise, an indicator-casing seated within the mortise and having transparent top and side walls, a removable top plate having an 90 observation-opening and serving to confine the casing in position, an indicator or gage-mark on the top, and degree-indicating marks on each of the transparent side walls, a gravity-indicator having a pivot-stud supported 95 by said side walls, said indicator comprising a plurality of substantially radial arms provided with designating-marks arranged at angles of ninety degrees from each other and a central depending weighted portion, the 100 weight and portion of each of the horizontal arms being disposed in a plane below the pivot-point of said indicator.

In testimony whereof I affix my signature in presence of two witnesses.

DANIEL NEWTON ALLARD.
